UNITED STATES PATENT OFFICE.

ROBERT E. HAMMER, OF PHILADELPHIA, PENNSYLVANIA.

CONVERTIBLE SOFA-BED.

SPECIFICATION forming part of Letters Patent No. 278,136, dated May 22, 1883.

Application filed April 16, 1883. (No model.)

To all whom it may concern:

Be it known that I, ROBERT E. HAMMER, a citizen of the United States, residing in Philadelphia, Pennsylvania, have invented certain 5 Improvements in Convertible Sofa-Beds, of which the following is a specification.

The main object of my invention is to so construct a convertible sofa-bed that the upholstered portions will be uppermost when the 10 piece of furniture is opened out into the form of a double bed as well as when it is in the form of a sofa, and this object I attain by combining with the seat for the sofa a reversible section hinged to said seat, both seat and 15 section being pivoted at their ends to hinged frame-pieces, as more fully described herein-after.

In the accompanying drawings, Figure 1 is a side view of the piece of furniture in the 20 form of a sofa; Fig. 2, a side view, showing it about being converted into a bed; Fig. 3, a section showing it in the form of a bed, and Fig. 4 a rear view of a sofa.

The main frame A consists of the end pieces, 25 *a a*, provided with legs and longitudinal bars *a' a'*. To the end pieces, *a a*, are hinged at *b* the portions *B B*, which form the arms of the sofa when the piece of furniture is used for that purpose, (Fig. 2,) while when it is used as a bed 30 these pieces *B* are turned over on their hinges to stand on the floor and form part of the bed-frame, as shown in Fig. 3. The arms *B* may be provided with any suitable form of spring-catch, *b'*, to retain them in position, (Fig. 1.) 35 These arms *B* carry the upholstered section *D*, which forms the seat of the sofa, and is pivoted to the arms by pivots *d*, (indicated by dotted lines in Figs. 1, and 3,) and to the rear of the seat-section is hinged the section *E*, which 40 forms the back of the sofa when so used, (Figs. 1 and 4,) this back being supported at the proper angle by bent arms *I*, carried by the pieces *B*. To the front of the seat-section *D* is hinged a similar upholstered section, *D'*, so that in the sofa form of the sofa-bed the section *D'* will be 45 folded under the seat-section with its upholstered side down, as indicated in Figs. 1 and 2. This section *D'* is pivoted to the end pieces, *a*, of the frame *A*, by means of the pivots *d'*.

The back of the seat-section *D* carries fixed 50 leg-supports *G G*, which are connected by radius-rods *g* to legs *H H*, hinged to the rear of the back-section *E*.

When the piece of furniture is in use as a sofa the arms *B* rest on the end pieces, *a*, of the 55 frame and are held by the catches *b'*, and the section *D*, with its upholstered side uppermost, is in position for use as the seat, while the section *D'* is folded underneath it, and the section *E* is supported at the proper angle by the arms 60 or pins *F*, to form the back of the sofa, as shown in Fig. 1. To convert this into a bed the catches *b'* are released and the arms *B* are turned on their hinges *b*, (Fig. 2,) to the position shown in Fig. 3, carrying with them the seat-section *D* and back *E*, the latter as the seat rises coming to a horizontal position on the arms or supports *F*, Fig. 2, while the section *D'* is turned over on its pivots until it assumes a horizontal position with its upholstered side 65 uppermost in line with the two other sections, as shown in Fig. 3. During these movements the seat-section *D* has maintained a nearly horizontal position, as will be seen in the several views. As the back-section *E* assumes a horizontal position the legs *H*, owing to their radius-rods *g*, will assume vertical positions, and with the legs *G* form supports for the sections 70 *E* and *D* of the sofa-bed.

I claim as my invention—

1. The combination of the frame and back and seat sections of a sofa-bed with a section, *D'*, hinged to the seat-section and pivoted to the frame, substantially as set forth.

2. The combination of the frame of a sofa-bed, hinged arm-pieces *B*, and back-section with a seat-section pivoted to the arm-pieces, and a section, *D'*, pivoted to the frame and hinged to the seat-section, substantially as described.

3. The combination of the frame *A* of a sofa-bed and hinged arm-pieces *B* with a seat-section pivoted to the arm-pieces, back-section hinged to the seat-section, and section *D'*, pivoted to the frame *A*, and also hinged to the seat-section, substantially as specified.

4. The combination of the frame *A* of a sofa-bed and hinged arm-pieces *B*, having supports *F*, with seat-section *D*, pivoted to the arm-

pieces, and back-section E, hinged to the said seat-section, substantially as described.

5. The combination of the frame and arm-pieces with seat-section, carrying legs G, and hinged back, carrying hinged legs H, and radius-rods g, connecting the legs G and H, substantially as set forth.

In testimony whereof I have signed my name to this specification in the presence of two subscribing witnesses.

R. E. HAMMER.
